WALL BOARD AND JOINT

Clement K. Swift, Upper Darby, Pa., assignor to
 MacAndrews & Forbes Company, Camden,
 N. J., a corporation of New Jersey

Application May 27, 1932. Serial No. 613,990

2 Claims. (Cl. 72—31)

This invention relates to a wall board having a joint made therewith and more particularly to the construction of the wall board joint.

One object of the invention is to provide a wall board as described, affording an improved wall construction made of a plurality of wall board units.

Another object of the invention is to provide a wall board and a joint made therewith which 10 will be more efficient in use than similar constructions heretofore available.

Another object of the invention is to provide a wall board having a joint made therewith which, when associated with a plurality of similar wall 15 board units to form a wall, affords a continuous plane surface to receive a coat of plaster or other material.

Another object of the invention is to provide a wall board joint construction which may easily 20 be fitted together despite discrepancies in the formation of the joint during manufacture.

Another object of the invention is to provide a wall board joint comprising a male and a female member, each having longitudinal beveled sides, 25 the angle of bevel of the male member being greater than the angle of bevel of the female member whereby a tight joint is provided which is effectively sealed against the penetration of plaster, or other coating material, inwardly of 30 the joint.

Another object of the invention is to provide a wall board joint comprising a male and female member, whereby the respective units associated 35 in the construction of a wall are maintained in coplanar alignment with respect to each other at all times.

A more specific object of the invention is to provide a wall board joint comprising a male and female member, each having longitudinal beveled 40 sides terminating in an abutment positioned normally with respect to the plane faces of the board, the angle of bevel of said male member being greater than the angle of bevel of the female member, effecting a firm, abutting joint, secured 45 against penetration of plaster or other coating material inwardly thereof.

A further object of the invention is to provide a wall board joint having novel compressible portions adjacent the longitudinal edges of the male 50 member, affording a tight, close fitting, and smooth jointure of a plurality of board units.

Other features and details of the invention are set forth hereinafter and disclosed in the accompanying drawing, in which:

55 Figure 1 is a view in perspective showing a

studding member to which is secured a plurality of wall board units;

Fig. 2 is a view in perspective similar to the disclosure in Fig. 1, showing a coating of plaster or other material applied to the outer surface of the 60 wall construction;

Fig. 3 is a fragmentary end elevation showing the wall board joint forming the subject of the present invention; and

Figs. 4 and 5 are views similar to Fig. 3 showing 65 modifications of the invention.

As is well known to those familiar with the present art, in wall structures made from a plurality of wall board units of the type forming the subject of the present invention and finished 70 with a coat of plaster or other material, there is a prevalent tendency for the plaster to crack on the line of jointure of two adjacent underlying wall board units. This cracking of the plaster finish has been eliminated to some extent by 75 fabricating the wall boards so that while more or less rigid of body, said boards yield materially as a result of the absorption of the maximum of expansion and contraction in the wall which is not possible in a dense, compact wall board 80 unit, which has little or no give, and therefore localizes at the joints.

Furthermore, the majority of wall board units having joints made therewith, are designed with the primary purpose of providing a substantial 85 recess in the wall surface at the line of jointure of the assembled wall board units, which is filled by the plaster finish for the purpose of reinforcing the finish at the joints. This feature of design is very unsatisfactory, because when the 90 plaster finish so applied, becomes dry, the portion of the plaster filling the recess is disposed in a plane offset from the plane of the wall proper.

It is well known to those familiar with the art 95 of plastering, that to disposed plaster in any but a single, continuous plane, creates a tendency for the plaster to crack at the juncture of the planes bounding the plaster. It is therefore desirable to provide a wall board and joint which, when associated with a plurality of similar units 100 in the construction of a wall, affords a continuous, smooth wall surface permitting every portion of the plaster finish to be applied to the underlying wall board units in coplanar relation. 105

The present invention provides a wall board unit and joint which is novelly constructed and easy to assemble and when joined with other similar wall board units in the construction of a wall, affords a continuous plane surface to re- 110

ceive the finishing coat of plaster or other material.

Referring now more particularly to the drawing, a preferred form of the wall board unit 1, made in accordance with the present invention, is rectangularly formed and secured to the customary wall studdings 2 with the long dimensions of the unit positioned normal to said studdings. The short ends of the wall board unit indicated by the numeral 3 are substantially flat and at right angles with respect to the parallel faces 4 and 5 of the board, one of said surfaces 4 and 5 being arranged for contact with the studdings 2, and the other forming the exposed or outer wall surface when in place.

One of the long edges of the wall board unit is cut to form a longitudinal projection 6 constituting the male member of a joint, the sides 6a thereof being beveled at an angle with respect to the parallel plane surfaces 4 and 5 of the board, and terminating at the outer edge of the projection in a substantially flat portion as shown in Fig. 3 of the drawing. The opposite edge of the wall board unit is provided with a complementary beveled groove 7 which is arranged to receive the corresponding longitudinal beveled projection 6 of a similar wall board unit.

For the purpose of providing the tight, wedge-like jointure of a plurality of board units associated in the construction of a wall, and to provide an effective seal against penetration of any coating inwardly of the joint, the beveled sides 6a of the male member 6 are formed at a greater angle with respect to the plane face of the board than are the beveled sides 7a of the complementary groove 7 as shown in Fig. 3 of the drawing.

As shown in Figs. 1, 2 and 3 of the drawing, the male and female sections of the preferred joint are each provided with a seat or an abutment 8 at the inner edge of the beveled sides 6a of the member 6 and at the outer edges of the beveled sides 7a of the groove 7, the said abutments extending at right angles to the plane surfaces 4 and 5 of the board.

The abutments 8 are particularly advantageous and afford a firm seat for the complementary members of the joint which precludes the possibility of wedging the male and female members together with sufficient force to cause the overlapping portions or sides of the female member to bulge outwardly and destroy the continuous plane surface provided for the reception of a coating material.

By the present invention a wall board and joint is provided which, when associated with a plurality of similar units in the construction of a wall, affords a tight, wedgelike joint therefor in a manner providing a continuous smooth wall surface for the application of a coating. The degree of difference in the angular position of the bevels of the projection and the groove, permits of easy assembly of a group of the units, and the provision of the abutments 8 in conjunction therewith, affords a tight joint between the units, which is thereby sealed against the penetration of the coating material inwardly of the joint and the adjacent units are maintained in aligned coplanar relation with respect to each other irrespective of varying degrees of pressure exerted thereagainst.

Other modifications of the invention may be had for example, and in Fig. 4 of the drawing is disclosed another form of the wall board joint wherein the male member 6 of the joint is pro-

vided with longitudinal feathers 9, 9 at the inner edges of the beveled sides 6a adjacent each of the parallel faces 4 and 5 of the board.

In the present instance the feathers 9 may be formed simultaneous with the cutting of the beveled side faces 6a of the projection, the said surfaces 6a being cut by means of a saw, or any other cutting means, from the apex of the projection 6 angularly in the direction of the plane surfaces 4 and 5 of the board, and it should be particularly noted that the bevel surfaces 6a, terminate prior to intersecting the plane faces 4 and 5 of the board, thus forming the small feathers 9, 9 which project beyond the inner edges of the beveled faces 6a in a reverse bevel having a width substantially equal to that of the saw or other tool used in cutting the bevels 6a.

By reason of the relatively small size of the feathers 9, 9 they are inherently compressible to an extent sufficient to effect a tight seal to the joint which provides a wall having a continuous plane surface for the reception of a plaster finish or not, as the case may be. Furthermore, the compressibility of the feathers 9, 9 provides an expansion and contraction factor which, under certain conditions may be desirable in fibre wall boards which are of a yieldable and moisture absorbing nature.

Fig. 5 of the drawing discloses a further modification of the wall board joint which is substantially similar in design to that previously described, though not provided with the complementary abutting surfaces 8 as in Fig. 3 or the feather elements 9 adjacent the parallel plane surfaces of the unit as disclosed in Fig. 4 of the drawing.

From the foregoing it will be seen that the improved joint I have invented is characterized by a beveled or tapered projection and groove, both the projection and groove being substantially V-shaped with the angle included between the beveled faces of the projection being somewhat greater than the angle defined by the beveled faces of the groove, but it is to be understood that while I have set forth the particular embodiment of the present invention for purposes of description, it is not intended that the structure shall be limited thereto other than within the scope of the appended claims.

What is claimed is:

1. A wall board plaster base unit of yielding fibrous and moisture absorbable character adapted to receive a plaster-like coating on a surface thereof, including a longitudinal projection on one edge offset from the plane surfaces of said board, said projection having oppositely beveled sides disposed at equal angles with the plane of the faces of the board and terminating at its outer end in a substantially flat portion and at the inner ends thereof in abutments disposed at right angles to said plane faces and constituting the offsets, and the opposite edge of the unit having a beveled groove, the sides of which are disposed at a lesser angle than the beveled sides of the projection and terminate at their outer edges in abutments extending at right angles to the plane faces of the board, the cooperating faces of the projection and groove being dimensioned and arranged to limit contact between adjacent edges of associated units to the normally abutting areas and the areas immediately adjacent to said abutments while maintaining the inner portions of said faces out of contact with each other.

2. A wall board plaster base of yielding fibrous

and moisture absorbable character adapted to receive a plaster-like coating on a surface thereof, comprising a plurality of boards set edge to edge and having interlocking substantially V-shaped tongues and grooves, and abutting surface areas adjacent each side of said interlocking members and disposed at right angles to the plane of the faces of said boards, said beveled faces of the tongue of each board being cut on an angle greater than that between the beveled

faces of the groove of such board, and having the cooperating faces thereof dimensioned and arranged to limit contact between adjacent edges of associated units to the areas of the abutments and the areas immediately adjacent to said abutments while maintaining the inner portions of said faces out of contact with each other, so that when operably assembled they will form a plaster base having a continuous plane surface.
